UNITED STATES PATENT OFFICE.

LOUIS KLEIN, OF DES MOINES, IOWA.

DESIGN FOR A PICTURE-FRAME.

49,846.

Specification for Design.

Patented Nov. 7, 1916.

Application filed March 13, 1916. Serial No. 83,979. Term of patent 3½ years.

To all whom it may concern:

Be it known that I, LOUIS KLEIN, a citizen of the United States, and resident of Des Moines, in the county of Polk and State of Iowa, have invented a new, original, and ornamental Design for a Picture-Frame, of which the following is a specification, reference being had to the accompanying drawing, forming part thereof.

The figure shows a perspective view of a picture frame, embodying my invention.

I claim:

The ornamental design for a picture frame, as shown.

Des Moines, Iowa, March 6, 1916.

LOUIS KLEIN.
